UNITED STATES PATENT OFFICE.

EDWARD LYTTON, OF LONDON, ENGLAND.

FIRING MECHANISM FOR SMALL-ARMS.

1,240,068.

Specification of Letters Patent. Patented Sept. 11, 1917.

Application filed July 21, 1916. Serial No. 110,561.

To all whom it may concern:

Be it known that I, EDWARD LYTTON, a subject of the King of Great Britain, residing in London, England, have invented certain new and useful Improvements in Firing Mechanism for Small-Arms, of which the following is a specification.

This invention relates to firing mechanism for small arms and is designed to provide a 10 firing or trigger arrangement which can be operated to fire or discharge the arm with the smallest effort and without any tendency to throw the sight off the target and which at the same time will be safe against any accidental shock or jar to which the arm may 15 be subjected.

Small arms as at present constructed are fired or discharged by means of a trigger which on being pulled releases a spring operated firing pin which makes impact against a cap in the cartridge and causes it to explode and thus produce the firing of the bullet. The pulling of such trigger requires a certain amount of force and as the direction 25 of the force to be applied is somewhat downward as well as backward the tendency is to throw the sight of the arm off the target and thus produce a bad aim. This difficulty with the present form of trigger adds considerably to the time required for a man to 30 become efficient in the use of, for instance a rifle, and it is one aim of the present invention to reduce as much as possible the time required for such training.

The invention consists essentially in a firing device having toggle means which, when maintained at approximately the dead center position, are adapted to hold the firing pin or other operative mechanism at cock 35 and means for throwing the toggle off or over the dead center when the arm is to be fired.

The invention will be described with reference to the accompanying drawings which 40 show, by way of example and diagrammatically, one application of the invention to a rifle.

Figure 1 is a longitudinal section through the firing mechanism of the rifle.

Fig. 2 is a section on line 2-2 of Fig. 1.

Fig. 3 is a part section showing a modified arrangement.

Fig. 4 is a view similar to Fig. 3 showing a further modified arrangement.

In the drawings, *a* is the butt of the rifle, *b* is the magazine, *c* is the barrel, *d* is the bolt, *e* is the striker or firing pin, and *f* is the spring for operating the firing pin, and these parts may be of any ordinary or suitable construction.

Beneath or adjacent to the bolt *d* is arranged a stop *g* adapted to slide in a direction parallel to the firing pin *e*, say along the rod *h*. The stop *g* is secured to the free end of a toggle *j*, the other end of which is pivoted on a fixed pivot *k* suitably mounted in the rifle, and a spring *l* is provided on the rod *h* adapted to force the stop *g* along the rod and hold the toggle *j* in the extended or dead center position. The stop *g* engages a 65 catch *m*, which may or may not be a spring catch, on the firing pin, and when the toggle *j* is in the dead center position holds the firing pin at cock. When, however, the toggle is moved out of the dead center position 70 for any reason, the spring *f* of the firing pin being stronger than the spring *l* of the stop, the firing pin is driven forward to fire the gun.

To move the toggle out of or through the 80 dead center position a pin, slide or the like *n* is provided which preferably extends across the body of the rifle. The pin or the like *n* is provided with an inclined face *o* adapted when the pin is moved endwise to engage the 85 toggle *j* and push it out of the dead center position so as to release the firing pin, and so effect the firing of the rifle. The end of the pin *n* preferably projects out into a 90 countersunk or like recess on the face of the rifle body, so as to prevent its release or operation through any accidental engagement and a spring *o'* is preferably provided adapted to hold it pressed outward in the non-operative position.

To prevent any accidental shock, jar or the like releasing the firing pin, the pin or slide *n* is preferably provided with a safety catch *p* adapted to prevent the closing of the toggle should any such shock or jar throw it 100

out of the dead center position. The face of the catch p is preferably inclined as shown to permit of the toggle when the firing pin is cocked taking the dead center position under the action of the spring z .

In the arrangement shown in Fig. 3 the stop g and slide h are dispensed with and the free end of the toggle is connected to a rotary catch g' adapted to engage the catch m on the firing pin and which must in this case be a spring catch. The catch g' is provided with a spiral spring g^2 adapted to rotate it into the engaging position, that is the position in which the toggle takes the extended or dead center position. The operating pin or slide n may be of exactly identical form to that described above.

In Fig. 4 another arrangement is shown in which the toggle may be set at the dead center, or cocked position, without the use of a spring. In this arrangement the free end of the toggle j is connected to a wheel q in a somewhat similar manner as to the catch g' in Fig. 3. Upon the periphery of the wheel are arranged a series of teeth r adapted to enter a series of rack teeth s on the side of the firing pin. In this arrangement it will be seen that when the firing pin is drawn back to the cocked position it will rotate the wheel q and cause the toggle j to take the dead center position and lock the firing pin. When the toggle is moved out of the dead center position by the pin or slide n which may be of exactly the same form as above described, the firing pin is released and causes the rifle to be fired.

To further insure against accidental firing of a weapon the toggle j may if desired be caused at the cocked position to slightly pass the dead center position to the opposite side to that at which it is released. A slide or cover may also be provided to cover and protect the operating end of the pin or slide n when the weapon is not in use.

Having thus described the nature of the said invention and the best means I know of carrying the same into practical effect, I claim:

1. A firing device for small arms comprising toggle means for holding the firing pin or the like at cock and a horizontally sliding member for releasing the toggle when the weapon is to be fired.

2. A firing device for small arms having toggle means which when maintained at approximately the dead center position are adapted to hold the firing pin or other operative mechanism at cock and means for throwing the toggle off or over the dead center when the arm is to be fired.

3. A firing device for small arms, comprising toggle means for holding the firing pin or the like at cock, and a sliding mem-

ber extending transversely across the body of the weapon for releasing the toggle when the weapon is to be fired.

4. A firing device for small arms, comprising a toggle lever, a stop linked to the free end of said toggle lever and holding the firing pin or the like at cock, the said stop being actuated by the firing pin to move the toggle lever out of its extended position when the weapon is fired.

5. A firing device for small arms, comprising toggle means for holding the firing pin or the like at cock, means for releasing the toggle when the weapon is to be fired, and means for preventing the release of the toggle by any shock or jar, after it has been set.

6. A firing device for small arms comprising a stop adapted to engage the firing pin when at cock, a toggle adapted to hold the stop in the cocked position when it is in or approximates to the dead center position, means for releasing the toggle from the dead center position to fire the weapon and means for returning the toggle to the dead center position when the firing device is cocked.

7. A firing device for small arms comprising toggle means for holding the firing pin or the like at cock, means for releasing the toggle when the weapon is to be fired, comprising a pin or slide having an inclined face adapted when it is moved endwise to push the toggle out of the dead center position.

8. A firing device for small arms comprising toggle means for holding the firing pin or the like at cock, means for releasing the toggle when the weapon is to be fired, comprising a pin or slide having an inclined face adapted when it is moved endwise to push the toggle out of the dead center position, and means for preventing the release of the toggle should the weapon receive a shock or jar consisting of a catch on the toggle releasing pin adapted normally to prevent the release of the toggle.

9. A firing device for small arms, comprising a toggle lever having one end connected to the body of the weapon, a rotary stop linked to the other end of said toggle lever and adapted to hold the firing pin in the cocked position, and a sliding member for releasing the toggle when the weapon is to be fired.

10. A firing device for small arms comprising a toggle, a rotary stop adapted to hold the firing pin in the cocked position when the toggle is in the dead center position, means for releasing the toggle when the weapon is to be fired, and means adapted to rotate the stop into the engaging position after the weapon has been fired.

11. A firing device for small arms, comprising a firing pin having a series of teeth formed thereon, a rotary stop having teeth adapted to engage the teeth of the firing pin, and a toggle, the free end of which is attached to the rotary stop in such a manner that when the toggle is extended the firing device is held at cock and when the toggle is liberated the firing device is released, the teeth on the firing pin and the rotary stop being adapted to return the toggle to the dead center position when the firing pin is drawn back to be set at cock.

5 In testimony whereof I have signed my name to this specification in the presence of 15 two subscribing witnesses.

10 EDWARD LYTTON.
